UNITED STATES PATENT OFFICE

118,155

DESIGN FOR A TOOTH BRUSH

Cyril M. Bosak, Old Forge, Pa.

Application August 31, 1939, Serial No. 86,989

Term of patent 14 years

To all whom it may concern:

Be it known that I, Cyril M. Bosak, a citizen of the United States, residing at Old Forge, in the county of Lackawanna and State of Pennsylvania, have invented a new, original, and ornamental Design for a Tooth Brush, of which the following is a specification, reference being had to the accompanying drawing, forming part thereof.

The dominant features of my design reside in the portions shown in full lines.

I claim:

The ornamental design for a tooth brush, as shown and described.

CYRIL M. BOSAK.
